UNITED STATES PATENT OFFICE.

SAMUEL M. RIKER, OF CHESTER, NEW JERSEY.

BELT BUCKLE.

Application filed September 2, 1922. Serial No. 585,986.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates to improvements in belt buckles; and the invention has reference, more particularly, to a novel clamp-plate adapted to be actuated by a pivoted cam-lever, said clamp-plate being provided 20 with a novel arrangement and construction of belt-biting or gripping elements.

The invention has for its principal object 25 to provide a belt buckle with a novel cam actuated clamp-plate having a peculiarly constructed belt-biting or gripping structure at its free end portion whereby said free end portion will yieldably cooperate with the actuating cam when encountering extra thick or hard belt members, so as to avoid placing 30 strains upon the cam device or the pivotal connections of the latter with the buckle body (which strains tend to either distort the cam device or dislodge the same from operative pivotal relation to the buckle body), 35 and yet will nevertheless cause the biting or gripping elements at said free end portion of the clamp-plate to firmly and securely grip or bite the belt member so as to retain the latter in desired adjusted fastened 40 relation about the waist of the wearer.

The invention is clearly illustrated in the accompanying drawings, in which:—

Fig. 1 is a central longitudinal section of the novel improved belt buckle made according to and embodying the principles of this invention; Fig. 2 is a transverse section, taken on line $x-x$ in said Fig. 1, showing the actuating cam in operative relation to the clamp-plate; Fig. 3 is a similar transverse section, showing the actuating cam in released relation to the clamp-plate; Fig. 4 is a plan view of the novel construction of clamp-plate removed from the buckle as-

sembly; Fig. 5 is a fragmentary central longitudinal section, similar to that shown in Fig. 1, but illustrating a modified arrangement for mounting the novel clamp-plate, and also illustrating a modified form of actuating cam; and Fig. 6 is a perspective view of a modified form of the novel clamp-plate.

Similar characters of reference are employed in all of the hereinabove described views, to indicate corresponding parts.

Referring now to the drawings, the novel construction of belt buckle comprises a main body consisting of a face or front-plate 7 (curved longitudinally as shown if desired), side flanges 8 springing rearwardly from the longitudinal margins of said face or front plate, and inwardly bent keeper flanges 9 connected with the margins of said side flanges to lie in a plane substantially parallel to and spaced rearwardly from the plane of said face or front plate 7. Said side flanges 8 are provided at one of their ends with rearwardly projecting perforate ears or extensions 10. Said keeper flanges 9 terminate short of said ears or extensions 10, thereby providing laterally disposed shoulders 11 adjacent to said ears or extensions 10.

Pivottally connected between said ears or extensions 10, is a clamp-plate actuating cam device, the same comprising a transverse bar 12 having journal portions 13 projecting from its respective ends. Said transverse bar 12 is mounted to extend transversely between said ears or extensions 10, with its journal portions 13 pivoted in the perforations or openings of said ears or extensions. Integrally connected with said transverse bar 12 is an outwardly projecting lever portion 14, which is preferably of loop form to provide an opening 15 at its free end to receive the loop 16 of the attached end of the belt member. Integrally connected with the central portion of said bar 12 is a cam-member 17, which is doubled beneath the bar to eccentrically off-set the same relative to the axis of said bar. Said cam-member may spring from the forward edge of said bar (as shown in Figs. 1, 2, and 3), or the same may spring from the rearward edge of said bar (as shown in Fig. 5), as may be deemed desirable. The outer or

operative face of said cam-member 17 is provided with a grooved or channeled seat 18 extending across the same. (see Fig. 3).

The novel clamp-plate (to be subsequently described in detail) may be pivotally attached to pivotal supporting members 19, such as shown in Figs. 1, 2, and 3, and the purpose and functioning of which are clearly described in my prior application for United States Letter Patent, filed February 10, 1922, Serial No. 535,432/15; or the said novel clamp-plate may be pivotally attached directly between the ears or extensions 10 at points spaced rearwardly from the pivotal connection of the actuating cam device, as shown in Fig. 5. In either case, it is preferable to pivot or fulcrum said clamp-plate upon a transverse rod 20, although it will be understood that other forms of pivotal mounting or connections therefor may be provided.

The reference character 21 indicates the novel clamp-plate, having at its rearward end a bearing portion 22 for pivotally engaging the same upon said transverse rod 20. Said clamp-plate 21 extends outwardly or forwardly beneath said bar 12 and its cam-member 17, with its free end portion terminating adjacent to the adjoining lateral margin of said face or front-plate 7. The lateral edge of said free end portion of said clamp-plate 21 is formed to provide, at its respective outer portions adjacent to the longitudinal sides of the clamp-plate, a pair of inwardly turned edge members 23 adapted to form belt-biting or gripping elements, and said lateral edge of said free end portion is formed to provide a raised yieldable edge-portion 24 which is outwardly offset from the plane of said inwardly turned edge members 23, and which extends laterally intermediate the same so as to be alined with and lie in the path of movement of the cam-member 17. In forming the respective edge members 23 and yieldable edge-portion 24 the same may be shaped by die operation so as to merge or curve one into the other, as shown in Figs. 1 to 5 inclusive, or the edge portion of the clamp-plate may be longitudinally slit intermediate the edge members 23 and yieldable edge portion 24 as shown in Fig. 6. Formed in the body of said clamp-plate 21 to the rear of the free end portion thereof, is a laterally extending lock rib 25 with which the grooved or channeled seat 18 of the cam-member 17 is designed to interlock when said cam-member is moved into actuating engagement with said clamp-plate.

When the lever portion 14 is swung in a counterclockwise direction, the cam-member 17 is moved away from the clamp-plate 21, thus freeing the latter from operative clamping engagement with the free or adjustable end 26 of the belt member, leaving

the latter but loosely engaged by the clamp-plate so that the same may be withdrawn from the buckle.

When fastening the belt member about the waist of the wearer, the free or adjustable end 26 is inserted between the side flanges 8 to pass forwardly through the space intermediate the face or front plate 7 and the keeper flanges 9, and thence beneath the clamp-plate 21, the cam member 17 being at the time released from actuating engagement with said clamp-plate. When the belt member is adjusted to desired tension about the waist of the wearer, the lever portion 14 is swung in clockwise direction to move the cam-member 17 into actuating engagement with the end of the clamp-plate until the cam-member seat 18 interlocks with the lock rib 25 of the clamp-plate. This operative movement of the cam-member 17 presses or swings the free end of the clamp-plate towards the belt end 26 thereby forcing the biting or gripping elements formed by the inwardly turned edge members 23 into biting or gripping engagement with said belt end. Before the cam-member 17 attains its interlocked relation to the clamp-plate 21, its free end moves in passing engagement with the free edge portion of the clamp-plate. If said free edge portion possesses a continuous inwardly turned biting or gripping edge, and if the belt member happens to be extra thick or made of very tough or unyielding material, such, for example, as bridle-leather, a very considerable resistance to the inward swing of the clamp-plate is encountered, which is transmitted to the cam-member with the result that the latter or the bar carrying the same is frequently distorted or bent out of shape, or the bar is dislocated from its operative pivotal connection with the main body of the buckle. Such occurrences are avoided however in the present invention, since the free edge portion of my novel construction of clamp-plate provides the inwardly turned or biting edge-members 23 only towards the sides of the clamp-plate, and that part of said edge-portion intermediate said biting edge-members 23 is formed to provide the outwardly off-set yieldable edge-portion 24 which alone is engaged by the passing cam-member. Such off-set yieldable edge portion 24 is approximately of the same width as the cam-member, and is by virtue of its off-set relation to the biting edge-members 23 held away from engagement with the belt-end 26, consequently when the cam-member thrusts the biting edge-members 23 into engagement with an extra thick or resistant belt member, said yieldable edge-portion will slightly spring or yield to the thrust of the cam-member so that the extra strain is compensated for, and the likelihood of deformation or dislocation of the cam-

member under such strain is eliminated. It will thus be apparent that the belt buckle structure as a whole, more readily adapts itself for use with various kinds and thicknesses of belt members without danger of such structure being rendered inoperative.

I am aware that some changes may be made in the various arrangements and combinations of the devices and parts, as well as in the details of the construction of the same, without departing from the scope of this invention as set forth in the foregoing specification, and as defined in the appended claims. Hence, I do not limit my invention to the exact arrangements and combinations of the various devices and parts as described in said specifications nor do I confine myself to the exact details of the construction of said parts as illustrated in the accompanying drawings.

I claim:-

1. A belt buckle comprising a main body, a pivoted cam-member having an actuating lever portion, a pivoted clamp-plate having its free end portion extending between the front portion of said main body and said cam-member, said clamp-plate having inwardly turned biting means at its free end, and a yieldable outwardly off-set portion also at its free end and alined in the path of movement of said cam-member.

2. A belt buckle comprising a main body, a pivoted cam-member having an actuating lever portion, a pivoted clamp-plate having its free end portion extending between the front portion of said main body and said cam-member, said clamp-plate having inwardly turned biting edge members formed adjacent to the ends of its transverse free edge portion, and a yieldable outwardly off-set edge portion intermediate said biting edge members and alined in the path of movement of said cam-member.

3. A belt buckle comprising a main body, a pivoted cam-member having an actuating lever portion, a pivoted clamp-plate having its free end portion extending between the front portion of said main body and said cam-member, said clamp-plate having inwardly turned biting edge members formed adjacent to the ends of its transverse free edge portion, a yieldable outwardly off-set edge portion intermediate said biting edge members and alined in the path of movement of said cam-member, and means mutually associated with said clamp-plate and said cam-member to interlock the same in their operated relation one to the other.

4. A belt buckle comprising a main body, a pivoted cam-member having an actuating lever portion, a pivoted clamp-plate having its free end portion extending between the front portion of said main body and said cam-member, said clamp-plate having inwardly turned biting means at its free end,

a yieldable outwardly off-set portion also at its free end and alined in the path of movement of said cam-member, and means mutually associated with said clamp-plate and said cam-member to interlock the same in their operated relation one to the other.

5. A belt buckle comprising a main body, a pivoted cam-member having an actuating lever portion, pivoted supporting arms capable of a limited movement toward and away from the front portion of said main body, a clamp-plate carried by said supporting arms with its free end portion extending between said cam-member and said front portion of said main body, said clamp-plate having inwardly turned biting means at its free end, and a yieldable outwardly off-set portion also at its free end and alined in the path of movement of said cam-member.

6. A belt buckle comprising a main body, a pivoted cam-member having an actuating lever portion, pivoted supporting arms capable of a limited movement toward and away from the front portion of said main body, a clamp-plate carried by said supporting arms with its free end portion extending between said cam-member and said front portion of said main body, said clamp-plate having inwardly turned biting means at its free end, a yieldable outwardly off-set portion also at its free end and alined in the path of movement of said cam-member, and means mutually associated with said clamp-plate and said cam-member to interlock the same in their operated relation one to the other.

7. A belt buckle comprising a main body, a pivoted cam-member having an actuating lever portion, pivoted supporting arms capable of a limited movement toward and away from the front portion of said main body, a clamp-plate carried by said supporting arms with its free end portion extending between said cam-member and said front portion of said main body, said clamp-plate having inwardly turned biting edge members formed adjacent to the ends of its transverse edge portion, and a yieldable outwardly off-set edge portion intermediate said biting edge members and alined in the path of movement of said cam-member.

8. A belt buckle comprising a main body, a pivoted cam-member having an actuating lever portion, pivoted supporting arms capable of a limited movement toward and away from the front portion of said main body, a clamp-plate carried by said supporting arms with its free end portion extending between said cam-member and said front portion of said main body, said clamp-plate having inwardly turned biting edge members formed adjacent to the ends of its transverse edge portion, a yieldable outwardly off-set edge portion intermediate

said biting edge members and alined in the path of movement of said cam-member, and means mutually associated with said clamp-plate and said cam-member to interlock the 5 same in their operated relation one to the other.

In testimony that I claim the invention set

forth above I have hereunto set my hand this 29th day of August, 1922.

SAMUEL M. RIKER.
